United States Patent Office.

JAMES NELSON AND HARMON G. ELLSWORTH, OF LOCKPORT,
NEW YORK.

Design No. 3,638, dated August 24, 1869.

DESIGN FOR SLEIGHS.

The Schedule referred to in these Letters Patent and making part of the same.

To all whom it may concern:

Be it known that we, JAMES NELSON and HARMON G. ELLSWORTH, of Lockport, in the county of Niagara, and State of New York, have invented a new and valuable Design for Sleighs; and we do hereby declare that the following is a full, clear, and exact description of the same, reference being had to the annexed drawing, making a part of this specification, and to the letters and figures of reference marked thereon.

Figure 1, of the drawings, is a side view of our sleigh;

Figure 2 is a rear view; and

Figures 3 and 4 are details.

The letters B, of the drawing, represent the panels, and letters D the star, which are respectively plain

and silver-plated. A duplicate of the side panel B is made and attached to the opposite side of the sleigh.

The mouldings, secured by screws, are shown by the letters E, and the form of our sleigh is represented by the drawing, taken as a whole.

What we claim as our invention, and desire to secure by Letters Patent, is—

The design for a sleigh, herein set forth and shown.

In testimony that we claim the above, we have herenuento subscribed our names, in the presence of two witnesses.

JAMES NELSON.

Witnesses: HARMON G. ELLSWORTH.

CHARLES H. SQUIRES,

JAMES CARMEN.
